UNITED STATES PATENT OFFICE.

KARL SCHWARZ, OF NUERMBERG, GERMANY, ASSIGNOR TO MASCHINENFABRIK AUGSBURG-NUERMBERG A. G., OF NUERMBERG, GERMANY.

CYLINDER.

1,107,850.

Specification of Letters Patent. Patented Aug. 18, 1914.

Application filed March 18, 1913. Serial No. 755,070.

To all whom it may concern:

Be it known that I, KARL SCHWARZ, a subject of the German Emperor, residing at Nuremberg, in the county of Mittelfranken and State of Bavaria, Germany, have invented certain new and useful Improvements in Cylinders, of which the following is a specification.

This invention has reference to cylinders for double acting two-cycle internal combustion engines and pertains particularly to cylinders to be used in engines for ships.

Accordingly, the present invention has for its purpose to produce cylinders of simple castings embodying effective cooling devices. Furthermore, very short cylinders are constructed of the relatively lowest weight possible.

In order to render the invention entirely clear reference is had to the accompanying drawing in which a cylinder is represented in longitudinal, axial section which embodies in desirable form the present improvements.

The entire cylinder consists chiefly of four castings of which two *a*, *b* form the upper half of the cylinder and two the lower one. Each of two such castings form one half of the cylinder. Taking, for instance, the lower half of the cylinder shown on the drawing, it is seen that the casting *c* forms one half *f* of the inner cylinder wall, and the casting *d* with the portion *g* forms the outer cylinder wall, while the flanges *h* and *i* serve for connecting the two walls.

The casting *d* forms with its top portion one half of the exhaust port or channel *k*. The tubular castings *d* and *b*, and the other parts are connected by means of flanges *l*. In order to obtain a very tight connection the tubular part *d*, may be applied in a heated condition and allowed to cool whereby a resulting shrinkage produces a perfect union. The exhaust channel or port *k* is connected to the inner cylinder wall by means of stuffing boxes *o*, as shown on the drawing, or this connection may be effected by shrinking the exhaust port upon the cylinder.

In order to effect the circulation of water for cooling purposes in the desired manner openings *p* are provided in the wall *i* through which openings the cooling water from the space *r* passes into the space *s*. The cooling jacket with the spaces *s* is provided

with several devices *q* for the purpose of forcing the cooling water with great speed along the cylinder wall *f*.

Thus the invention presents a series of advantages: By the division of each half of the cylinder into two parts only relatively simple castings are required. The division of the inner cylinder wall in the plane *A*, *B* and the provision of the walls *k* of the exhaust port or channel on the inner cylinder wall by means of stuffing boxes *o* or by heating these parts and allowing them to cool in the desired location, unequal expansions of heat in the wall parts can not injure the same because the single wall parts may slightly shift one toward the other whereby the occurrence of cracks is prevented. The parts *b*, *d* being separate parts render it possible that they, as well as the inner cylinder wall *f*, may be turned off and thus reduced, accordingly, superfluous thicknesses of the walls are avoided and the lowest possible weight of these parts is attained. If desired the parts *b*, *d* may be united by flanges *n*, *n*. As the space *s* within the cooling arrangement is accessible devices may be provided for securing an effective cooling, as shown on the drawing in form of the tubes *q* therein applied.

I claim as my invention:

1. A cylinder for double acting two-cycle internal combustion engines composed essentially of four parts, the cylinder being divided in a plane passing through the exhaust channel and perpendicular to the cylinder axis, each of the castings at either side of the division line consisting of one half of the interior cylinder wall, a portion of an outer part forming a water jacket adjoining the cylinder end, and connecting flanges for joining the jacket and the cylinder wall to the corresponding parts of the other casting.

2. A cylinder for double acting two-cycle internal combustion engines composed essentially of four parts, the cylinder being divided in a plane passing through the exhaust channel and perpendicular to the cylinder axis, each of the castings at either side of the division line consisting of one half of the interior cylinder wall, a portion of an outer part forming a water jacket adjoining the cylinder end, connecting flanges for joining the jacket and the cylinder wall to the corresponding parts of the other casting, and

stuffing boxes for tightening the adjoining parts near the division line.

3. A cylinder for double acting two-cycle internal combustion engines composed essentially of four parts, the cylinder being divided in a plane passing through the exhaust channel and perpendicular to the cylinder axis, each of the castings at either side of the division line consisting of one half of 10 the interior cylinder wall, a portion of an outer part forming a water jacket adjoining the cylinder end, connecting flanges for join-

ing the jacket and cylinder wall to the other casting, stuffing boxes for tightening the adjoining parts near the division line, and 15 conduits for the cooling water within the space of the water jacket.

In testimony whereof I affix my signature in presence of two witnesses.

KARL SCHWARZ.
